UNITED STATES PATENT OFFICE

WILLIAM H. SAUVAGE, OF NEW YORK, N. Y., ASSIGNOR, BY MESNE ASSIGNMENTS, TO
GOULD COUPLER COMPANY, OF NEW YORK, N. Y.

SLACK ADJUSTER

Application filed February 9, 1925. Serial No. 7,955.

This invention relates to slack adjusters and more particularly to automatic slack adjusters for the brake rigging of railway cars, although, as will appear from the following 5 description, many features are applicable to other parts of the brake rigging where the effective length of a connecting member, for example, is adapted to be varied as slack or excess travel occurs.

10 One of the objects of the present invention is to provide a slack adjuster of the above general character which will be automatic in its operation, and have relatively few parts whereby the device may be inexpensively 15 manufactured, assembled and installed.

20 A further object is to provide a mechanism of the above general character, adapted to be supported from the car body, yet to cooperate with the truck brake rigging in a reliable and efficient manner.

25 A further object is to provide a mechanism of the last above mentioned character which will permit of relative movement between the car body and the truck as when going around curves, for example, without in any 30 way actuating the slack adjuster.

Other objects will be in part obvious from the annexed drawings and in part indicated in connection therewith by the following analysis of this invention.

The invention accordingly consists in the features of construction, combination of parts and in the unique relations of the various members and in the relative proportioning and disposition thereof, all as more clearly outlined hereinafter.

To enable others skilled in the art so fully to comprehend the underlying features thereof that they may embody the same by numerous modifications in structure and relation contemplated in this invention, drawings depicting a preferred form have been annexed as part of this disclosure, and in such drawings like characters of reference denote corresponding parts throughout all the views, in which—

50 Figure 1 is a vertical elevational view partly in section, showing such parts of a truck and its brake mechanism and car body as is necessary to fully understand the invention;

Figure 2 is a sectional elevational view of the slack adjuster; and

Figure 3 is a plan view of the slack adjuster.

Referring now to the drawings in detail 55 and more particularly to Figure 1, 5 indicates the draft sill of a car body and 6 the truck bolster having the usual king pin or pivotal connection 7. To one side of the truck bolster is mounted a hanger 8 for the 60 dead lever 10, which is connected at its lower end with push rod 11 pivotally connected in train to the lower end of a live lever 12. The upper end of the live lever is connected to a pull rod 13, which, in turn, is actuated by 65 the brake actuating mechanism of any desired type. The live and dead levers are provided with brake beams 14, all of well known general construction.

Secured to the underside of the draft sill 70 5 is a bracket 15 carrying the slack adjuster mechanism hereinabove described and shown more clearly in detail in Figures 2 and 3.

This slack adjuster mechanism comprises 75 a casing 16 provided with supporting and attaching means such as bolt holes 17, and is hollow to provide a housing 18 through which a take up rod 20 is free to pass. This take up rod is provided with a stop 21 at one end and an eye 22 at its opposite end. Connected 80 to the eye 22 and the upper end of the dead lever 10 are a plurality of links to form a chain 23 thereby to provide a flexible connection therebetween which permits a relative turning movement between the slack adjuster 85 and the truck brake rigging as, for example, when the car is rounding a curve.

Within the housing 18 are a plurality of holding dogs 24 which consists preferably of a pair of rectangular steel plates having an 90 opening in their central part through which the rod 20 is free to pass. A spring 25 mounted upon a boss 26 is interposed between one wall of the housing 18 and the side of one of the dogs 24, thereby normally to hold 95 the dogs in canted position. Case hardened edges of the holes through the dogs engage the take up rod 20 to normally prevent any relative movement of the rod towards the right.

Adjacent this part of the slack adjuster and movable relatively to the casing 16, is a second housing 27 also providing a chamber 28 in which a dog 30 is mounted similar to those just described. A spring 31 is interposed between the side wall of the housing and the dog to hold the same in canted position. An adjusting rod 32 is threaded at 33 into the side wall of the housing and the opposite end 34 is connected by means of a rod 35 with a chain 36, the opposite end of which chain is connected to a friction clamp 37 upon the pull rod 13. This flexible chain provides a certain amount of lost motion and insures uniform travel of the brake actuating mechanism. In other words, there will be no operation of the slack adjuster until the pull rod 13 moves sufficiently towards the right to take up all of the slack in the chain 36. A spring 40 surrounds the rod 32, and normally maintains the housing 27 in close proximity to the fixed housing 18.

Having described the construction, the operation thereof is substantially as follows: In normal actuation, a movement of the pull rod 13 towards the right will actuate the live and dead levers through connecting rod 11, the latter being supported from the underside of the spring plank 38, to carry the brake shoes into engagement with the car wheels in the well known manner. If any excess travel occurs exceeding that provided for by the lost motion device or chain 36, the pull rod 35 is then moved a corresponding amount which, in turn, actuates the rod 32 to move the housing 27 towards the right and further compress the spiral spring 40 surrounding the adjusting rod. It will be understood that the dog 30 is free to move bodily in this right hand direction, and the dogs 24 prevent a reactive movement of the rod 20 connected to the upper end of the dead lever. On release of the brakes, the spring 40 expands to return the housing 27 to normal position, and, during this movement, the case hardened edge of the dog 30 bites into the take up rod 20 to carry the same towards the left an amount corresponding to the compression of the spring 40 on the excess travel of the brake rigging. This movement causes the adjusting rod to pass freely in a left hand direction through the dogs 24 which thereafter permanently hold this excess travel.

It will be noted that the underside of the housing 27 is provided with a tubular portion 41 carrying a pin 42 which is substantially equal in length to the normal space between the dog 30 and the adjacent dog 24. When it is desired to restore the parts to normal position, as in replacing brake shoes, for example, the lower end of the dog 30 is moved towards the left. This movement through the pin 42 will carry the lower ends of the dogs 24 likewise to the

left until they occupy a position normal to the axis of the take up rod 20 and in that position the adjusting rod is free to be moved in either direction. After the new brake shoes are installed, the first application of the brakes will repeat the operation above described, taking up all of the excess travel during a single complete cycle of operation, that is, application and release of the brakes.

From the above it will be seen that the present invention provides a simple and practical apparatus well adapted to accomplish among others all of the objects and advantages herein set forth.

Without further analysis, the foregoing will as fully reveal the gist of this invention that others can by applying current knowledge readily adapt it for various applications without omitting certain features that from the standpoint of the prior art fairly constitute essential characteristic features of the generic and specific aspects of this invention, and, therefore, such adaptations should and are intended to be comprehended within the meaning and range of equivalency of the following claims.

I claim:

1. In an apparatus of the character described, in combination, a slack adjuster casing supported from the car body, a second casing movable relatively with respect thereto, an adjusting rod connected with the brake actuating mechanism, a swing adapted to be compressed on excess travel of the brake rigging, a take up rod connected with the upper end of the dead lever adapted to be actuated on release of the brakes after excess travel has occurred, flexible means associated with each of said connections adapted to permit relative movement of the truck with respect to the adjuster, and means whereby both the temporary and permanent take up and holding means may be released by a single operation when it is desired to replace worn parts.

2. In an apparatus of the character described, in combination, a housing supported from the underside of the car body, a take up rod passing through said housing, permanent take up and holding means associated with said take up rod adapted to permit movement in one direction and normally prevent movement in the opposite direction, a second housing, an adjusting rod associated therewith, temporary take up and holding means therefor, and a compression spring adapted to be compressed on movement of said second housing when excess travel occurs, and means adapted to actuate said take up rod on release of the brakes when excess travel occurs, and a single device interposed between said temporary and permanent holding means for releasing one when the other is released.

3. In a slack adjuster, a housing supported from the underside of the car body, a take up rod passing through said housing, permanent take up and holding means associated with said rod, a second housing, an adjusting rod associated therewith, temporary take up and holding means therein, resilient means adapted to actuate said take up rod on release of the brakes when any excess travel occurs, and means interposed between said temporary and permanent take up and holding means for releasing one of said means when the other is released.

4. In a slack adjuster, temporary take-up means, permanent take-up means, and means acted on by one of said take-up means to effect release of the other.

Signed at New York city this 8th day of January, 1925.
